UNITED STATES PATENT OFFICE

ARTHUR J. JACKMAN, OF FOREST HILLS BOROUGH, PENNSYLVANIA, ASSIGNOR TO VESUVIUS CRUCIBLE COMPANY, OF SWISSVALE, PENNSYLVANIA, A CORPORATION OF PENNSYLVANIA

LADLE STOPPER CONSTRUCTION

Application filed October 2, 1929. Serial No. 396,749.

This invention relates broadly to ladle stopper constructions and more particularly to a ladle stopper construction providing protection from the contents of the ladle for the ladle stopper rod. The invention relates still more particularly to a ladle stopper construction embodying a preformed or pre-fired protective member for protecting the stopper rod.

Ladle stoppers are usually made of a material highly refractory to the action of molten metal such, for instance, as clay or clay and graphite compositions. These stoppers usually have a bore extending therethrough from top to bottom and have connected therewith a metal rod for raising and lowering the stopper. The metal rod may pass through the bore of the stopper and be connected therewith at the lower extremity of the stopper or, as is usually the case, there may be a headed bolt or pin entering the stopper from below and passing upwardly into engagement with the rod.

Whether the rod itself or a bolt or pin connected therewith extends through the bore of the stopper, it is necessary to have some connecting part exposed at the bottom thereof. The action of the molten metal contained in the ladle upon such a metal portion of the stopper construction has an exceedingly detrimental effect on such metal portion, often causing it to melt or fuse and thereby permitting the stopper and rod to become disengaged, whereupon the ladle loses its usefulness.

It has heretofore been attempted to obviate the disadvantage above noted by covering or protecting the extremity of the stopper rod or the pin or bolt connected therewith which extends through the bore of the stopper and is exposed at the bottom thereof. Such covering or protection has comprised a mass of mud or moist clay which has been applied to the metal portion so as to cover it and thus prevent any of the contents of the ladle from coming into direct contact therewith during use of the ladle. It has also heretofore been proposed to form a cavity in the bottom of the stopper and to have the stopper rod assembly terminate in

such cavity, the cavity being filled up with mud. However, the application of mud as a protective means for the metal portion of the stopper rod assembly, which would otherwise be exposed at the bottom of the stopper, has been most unsatisfactory due to the fact that the mud, through the operation of the ladle, becomes loosened or dislodged and in many instances either permits molten metal to enter the cavity in the bottom of the stopper or entirely drops out, thereby freely exposing the metal part to the action of the molten metal.

I provide a ladle stopper construction which obviates the disadvantages above noted and provides for substantially permanent protection for the portion of the stopper rod assembly which would otherwise be exposed at the lower portion thereof.

I provide a ladle stopper construction, comprising a stopper, a rod connected therewith, and a preformed protective member for the extremity of the rod.

I further provide a ladle stopper construction, comprising a stopper, a rod connected with the stopper and having its extremity within the body of the stopper, and a preformed protective member for the extremity of the rod.

Other objects and advantages of the invention will become apparent as the following description of certain present preferred embodiments thereof proceeds.

In the accompanying drawings I have shown certain present preferred embodiments of the invention, wherein

Figure 1 is a partial vertical cross-section through a ladle and its stopper assembly,

Figure 2 is an enlarged cross-sectional view through a stopper construction,

Figures 3 and 4 are views similar to Figure 2 through modified stopper constructions, and

Figure 5 is a perspective view of a protective member for use in a ladle stopper construction.

Referring more particularly to the drawings, reference numeral 2 designates generally a ladle having a refractory lining 3, and a metal outlet 4. Cooperating with the

outlet 4 of the ladle is a stopper 5 having a central bore 6 extending therethrough from top to bottom. The bore of the stopper is enlarged at the bottom to form a cavity 7 which tapers so that it decreases in size from the surface of the stopper inwardly.

A stopper rod 8 is provided for operating the stopper. This rod abuts the top of the stopper and is connected therewith by means of a pin 9 having a head 10 lying within the cavity 7, the opposite extremity 11 of the pin entering a cavity in the rod 8, the two being connected together by means of a key 12. Although the rod proper as shown 10 terminates above the stopper and is connected therewith by a pin and key, the rod itself may be so formed as to extend through the stopper so that a portion of the rod, instead of the head of the pin, will be exposed 15 at the bottom of the stopper. The word "rod" as used in the claims contemplates either the rod itself or the pin connected therewith.

Surrounding the stopper rod 8 above the 25 stopper 5 is a series of protective refractory sleeves 13 for protecting the rod from the action of the molten metal within the ladle. Therefore, every portion of the rod assembly 30 is protected from the action of the metal except the head of the pin 10.

For protecting the head of the pin I provide a preformed or pre-fired wedge member 14, adapted to enter the cavity 7 and to be firmly maintained in place therein and 35 against the head of the pin. The protective member 14 comprises a cylinder the end faces of which are substantially parallel to each other but non-perpendicular to the axis of the cylinder. This construction provides for maintaining the protective member 40 in place within the cavity 7 by contact between its edges and the faces of the cavity. The protective member is inserted into the mouth 45 of the cavity by moving it through the mouth thereof substantially in the direction of the axis of the protective member, and after such member is within the cavity it is permitted to turn through a small angle so as to assume the position shown in Figures 1 50 and 2. If the diameter of the mouth of the cavity be A, then the diameter of the protective member 14 is very slightly less than A to permit of movement of the protective member through the mouth of the cavity 55 axially of the cavity and axially of the protective member. After the protective member has entered the cavity and its upper face contacts with the head 10 of the pin, the protective member will automatically be turned by the relative action of such contacting parts to assume the position shown in Figures 1 and 2 wherein it is in effect wedged against the head of the pin so as to press upwardly thereagainst. The contact 60 of the edges of the protective member

with the face of the cavity prevents the member from turning back into such a position as to permit it to drop out through the mouth of the cavity. Preferably the upper face of the protective member does not 70 lie flat against the head of the pin but extends at a slight angle thereto, as shown, whereby a substantial stress exists, tending to maintain the protective member in place. This stress is imparted to the member 75 through the combined action of the pressure of it against the head of the pin and the bearing of its edges against the face of the cavity. Movement or jarring of the stopper, instead of loosening the protective member 80 tends to more tightly wedge it in place so that there is no danger of its dropping out. The protective member therefore serves as a substantially permanent and positive 85 means for keeping the head of the stopper rod assembly out of contact with the molten metal.

As the protective member is being introduced into the cavity a mass of mud 15 is also introduced to fill up the spaces both 90 above and below the protective member and thereby still more effectively seal the head of the pin out of contact with the molten metal. A small amount of mud is inserted 95 into the cavity ahead of the protective member to fill up the spaces around the head of the pin and along the edge of the member and after the member is in place the remaining portion of the cavity is filled up with 100 mud. The mud assists somewhat in insuring that the protective member will not drop out, but the protective member is firmly wedged in place independently of the mud and therefore the latter acts more in 105 the capacity of a sealing agent. In any event, when the preformed protective member is utilized a positive protection is provided which is not possible when mud alone is used, as has heretofore been customary 110 in the art. Even if some of the mud drops out the protective member and the mud above it will remain in place and effectively seal the head of the pin.

Figures 3 and 4 show modifications of the form of the protective member whereby 115 means is provided for more firmly and securely keeping in place the mud which is inserted below the protective member. In Figure 3 there is shown a protective member 14' having in its lower face a tapered cavity 16, into which a portion of the mud is inserted so that when the mud hardens it will be effectively keyed into the protective member which will prevent it from falling out. A similar provision is shown in Figure 4 120 wherein there is a protective member 14'' having on its lower face a tapered projection 17 for assisting in maintaining the mud in place. The mud is wedged between opposite sides of the projection 17 and the 125

130

face of the cavity in the stopper so as to prevent it from falling out.

The protective member is conveniently made by providing the end faces substantially parallel to each other and at an acute angle to the axis of the member. However, the faces need not necessarily be parallel as the same effect is obtained if one of the faces only is disposed at an acute angle with respect to the axis of the member. In fact, although I have shown and described certain present preferred embodiments of the invention, the same is by no means limited to such embodiments but may be otherwise variously embodied within the scope of the following claims.

I claim:

1. A ladle stopper construction, comprising a stopper having a hole in its bottom, a rod connected therewith, and a preformed protective member for the extremity of the rod, said member having a cross-section in one direction less than that of the mouth of the hole whereby to be loosely insertable into such hole.

2. A ladle stopper construction, comprising a stopper, a rod connected with the stopper and having its extremity within the body of the stopper, and a preformed protective member for the extremity of the rod, said member being substantially smooth longitudinally and being slidable into the body of the stopper during assembly of the ladle stopper construction.

3. A ladle stopper construction, comprising a stopper, a rod connected therewith, and a preformed protective member positioned over the extremity of the rod, said stopper and member having longitudinally slidably interfitting parts whereby to be adapted to be slidably connected with one another during assembly of the ladle stopper construction.

4. A ladle stopper construction, comprising a stopper, a rod connected therewith, and a protective member for the extremity of the rod and separate therefrom, such member and stopper having longitudinally slidably interfitting parts whereby to have wedging engagement with one another.

5. A ladle stopper construction, comprising a stopper, a rod connected with the stopper and terminating therein, and a wedge protective member for the extremity of the rod and separate therefrom and lying within the stopper.

6. A ladle stopper construction, comprising a stopper having a cavity tapering to increased size from the surface of the stopper inwardly, a rod connected with the stopper and terminating within the cavity, and a preformed protective member for the extremity of the rod held in the cavity.

7. A ladle stopper construction, comprising a stopper having a cavity increasing in

size from the surface of the stopper inwardly, a rod connected with the stopper and terminating within the cavity, and a protective member capable of entering the cavity in one position but adapted to be turned after entering so as to be maintained in place therein.

8. A ladle stopper construction, comprising a stopper having a cavity increasing in size from the surface of the stopper inwardly, a rod connected with the stopper and terminating within the cavity, and wedge protective means in the cavity whose size in one direction is only slightly smaller than the size of the mouth of the cavity, such means being adapted to assume a position across the cavity so as to be maintained in place therein.

9. A ladle stopper construction, comprising a stopper having a cavity increasing in size from the surface of the stopper inwardly, a rod connected with the stopper and terminating within the cavity, and a protective member whose size perpendicular to its longitudinal axis is less than the size of the mouth of the cavity but which when turned with its longitudinal axis at a small angle to the axis of the cavity will be maintained in place therein.

10. A ladle stopper construction, comprising a stopper having a cavity increasing in size from the surface of the stopper inwardly, a rod connected with the stopper and terminating within the cavity, and a protective member in the form of a cylinder whose faces extend at an acute angle to the axis thereof and adapted to enter the cavity.

In testimony whereof I have hereunto set my hand.
